CLAIM

The ornamental design for a modular device charging system, as shown and described.

DESCRIPTION

FIG. 1 is a front perspective view showing a modular device charging system of the present invention;

FIG. 2 is a rear perspective view thereof;

FIG. 3 is a top view thereof;

FIG. 4 is a front view thereof;

FIG. 5 is a rear view thereof;

FIG. 6 is a right side view thereof;

FIG. 7 is left side view thereof; and,

FIG. 8 is a bottom view thereof.

The broken lines in the figures depict environmental structure and portions of the modular device charging system that form no part of the claimed design.
